UNITED STATES PATENT OFFICE

JOHN WILLIAM HODGSON, OF AKRON, OHIO, ASSIGNOR TO THE MILLER RUBBER CO.,
OF AKRON, OHIO, A CORPORATION OF OHIO

PLUG-INSERTING NEEDLE

Application filed July 2, 1928. Serial No. 289,986.

My said invention relates to improvements in tire repair devices of the type employing a wire helix designed to be engaged with the stem of a rubber plug.

5 The present invention is aimed to provide a construction which may be made with a helix of lighter wire which facilitates the insertion of the stem of the plug, and which will be guarded in such a way that its coils 10 will not be subjected to strain when passed through the wall of the tire. To this end, the invention comprises the novel construction hereinafter described and defined by the appended claim.

15 The said invention is illustrated in the accompanying drawing in which:

Fig. 1 is a plan view of the tire repair device constructed in accordance with my invention with the sleeve in retracted position and 20 partly broken away and with the helix engaging the stem of the plug.

Fig. 2 is a similar view with the sleeve or guard in the position which it occupies when the needle is ready to be forced through the 25 tire wall.

Referring by reference characters to this drawing, the numeral 2 indicates the needle proper which has a cylindrical portion 2^a provided with a helical groove in which is seated and secured by brazing, welding, or 30 the like, the terminal portion of a wire helix 3 which is arranged in axial alignment with the needle and is provided with open coils, the exterior of which are not greater in diameter than the exterior diameter of the said 35 cylindrical portion.

The said cylindrical portion preferably terminates in an annular shoulder *a* for the purpose hereinafter described, and the needle is provided at the opposite end with a penetrating 40 point, and at a suitable distance back from said point with an eye to receive a pulling device; such for example, as a wire nail. 4 designates a protecting sheath which is in 45 the form of a tube or cylinder having a bore to slidably fit the helix, and the cylindrical portion carrying the same, and having adjacent its forward end, a reduced bore to provide an internal shoulder 4^a to coact with the 50 shoulder of the needle to limit movement of

the sheath in the direction of the plug 1. Said reduced bore snugly fits the needle, though freely slideable thereon, and the sheath is provided adjacent its forward or inner end with a beveled edge indicated at 4^b.

55 After the plug has had its stem inserted in the coils of the helix, as shown in Fig. 1, the sheath is moved towards the plug 1 until it completely incloses the coils of the helix, whereupon the needle can be readily passed 60 through the tire, carrying with it the sheath and inclosed helix and stem 1^a of the plug. When the head of the plug has been properly seated against the inside of the tire, the sheath 65 may be withdrawn and the helix disengaged from the plug.

Having thus described my invention, what I claim is:

Means for repairing a tire puncture comprising a needle having at one end an open 70 helix, a tubular sheath removably inclosing said helix, and means for limiting the movement of the sheath on the needle in the direction of the helix.

75 In testimony whereof, I affix my signature.

JOHN WILLIAM HODGSON.
